TELEVISION TRANSMITTER

Kurt Schlesinger, Berlin, Germany, assignor to
 Radioaktiengesellschaft D. S. Loewe, Berlin-
 Steglitz, Germany

Application April 5, 1935, Serial No. 14,846
 In Germany April 6, 1934

3 Claims. (Cl. 178—7.1)

The present invention relates to television transmitters which, on the same wave with the video signals, transmits synchronisation impulses. As well known, it is necessary in transmitters of this kind that the synchronisation impulses exceed to a certain extent the highest amplitudes of the video current, so that at the receiver a proper separation of synchronisation and video signals by means of an amplitude filter will be possible.

It has been proposed to ensure the said condition on the high frequency side of the transmitter by modulating e. g. the antenna current by the video signals so that it never decreases under a certain minimum value. The aerial current disappears entirely only when the aerial is disconnected from the high frequency generator by a switch operated by the synchronisation signals, the requirement that these signals possess an overwhelming amplitude as compared with the image signals thus being complied with.

According to the invention the correct amplitude ratio of video and synchronizing signals is already ensured on the low frequency side, i. e. prior to the entry of the modulating potentials into the high-frequency transmitter. It has already been shown in the application Ser. No. 725,743 in what manner a low-frequency mixing of the image signals and the synchronisation signals in this way may be brought about, for example by producing the synchronisation signals electrically by means of a special impulse connection and performing an electrical mixing at the output of the image current amplifier. The present application sets forth a special method in order to prevent the image potential peaks from becoming occasionally equal to or greater than the synchronisation peaks. The application accordingly relates to the combination of amplitude limiting means operating without inertia for the image current amplifier with the method previously set forth in the application Ser. No. 712,971 for the low-frequency mixing of synchronisation and image signals.

The invention will be more clearly explained by means of the accompanying drawing, in which

Fig. 1 shows the general scheme of a transmitter according to the invention, whilst

Fig. 2 shows a more detailed connection diagram.

Fig. 1 shows by way of example a transmission arrangement with low-frequency mixing. In the same 1 is the Nipkow disc of the transmitter, which scans the image in the known fashion and controls the image current amplifier 3 through the medium of a photo-cell 2, whilst a second photo-cell 4 behind a separate ring of apertures receives the line frequency. The latter is passed to a special impulse apparatus 5 which, as already described in detail in the application No.

725,743, and the construction of which is moreover not essential for comprehension of the present application, furnishes the lead 6 with signals of constant amplitude (for example 30 volts), constant direction (preferably negative, i. e. in the image black) and constant duration (for example 5% of the line period). The two outputs, i. e. the leads 6 and 7, the latter being the output of the video current amplifier 3, are connected to the input of a common high frequency transmitter 8. If the unmodulated aerial current is equal to half the maximum value the controlling voltage furnished by the amplifier 3 must obviously fulfil the following conditions:

1. In the negative direction it should never surpass a certain value lowering the antenna current to say 20% of its maximum amplitude. If it exceeds this amount, the amplitude filter of the receiver is no longer able to perform a reliable separation of the signals, and the synchronism is instantly destroyed.

2. In the positive direction it should not surmount the control range of the transmitter.

3. When employing films with rapidly varying transparency there should be provided a special regulating device which compensates electrically the variable light conditions, modulating or strengthening the contrasts of the image.

4. The device referred to under 1 should be capable of being adjusted and of operating independently of the devices referred to under 2 and 3.

Fig. 2 shows a form of embodiment of the peak value device according to the invention. In the train of the low frequency amplifier 3 there are shown a penultimate and a final amplifier tube 9 and 10 coupled by means of anode resistance 15 and condenser 16. Negative signals at the amplifier output 7 indicate positive signs at the grid of the final amplifier tube 10. At this point, in accordance with the invention, there is connected through the medium of a coupling condenser 11 a potential limiter consisting of a discharge tube 14, the anode of which is supplied with an adjustable bias of negative sign 13 over a series resistance 12. The tube 14 is preferably a gas-filled diode with small inner resistance, i. e., with high emission and small inner spacing. When the potential of the grid of the tube 10 surpasses that of 13 the emission of 14 accordingly occurs very suddenly. The limiting effect of the arrangement is improved by a series resistance 23. 23 should be small as compared with the capacitative input resistance of the tube 10 at the maximum image frequency, but large as compared with the discharge resistance of the tube 14. The signals, therefore, at the amplifier output 7 are unable to proceed beyond a negative surge value, the height of which may be adjusted by adjustment of the bias 13.

As regards the dimensioning of the coupling means 11—12 a time constant of approximately 10^{-2} seconds is desirable which is obtained by choosing 11 to .1 mf. and 12 to about .1 megohm. The latter resistance is relatively large in comparison to the anode resistance 15 of approximately 5000 ohms.

It is not sufficient to ensure that the negative peak values are constant if at the same time the degree of amplification of 3 has been incorrectly adjusted. If the amplifier is set to be too sensitive, it may occur for example that its output oscillation is already cut off proceeding from the centre. All values below the middle grey down to black would be made equal in the image, so that corresponding contours would not be visible at all. The applicant has already set forth in the application No. 725,743 that upon the transmission care requires to be taken by means of an automatic regulator that the frequently occurring considerable fluctuations in the transparency of the film and the copying brilliancy are intercepted. In addition to these conditions it is necessary that this peak value regulator regulates only the opposite amplitude of the signals not already limited by the tube 14. A regulating tube of this character, operating a directional amplifier, is designated 17, its anode potential source 18, its anode resistance 19, its grid bias regulator 22. From the point 20 a regulating lead passes to the grid of the tube 9. The grid of the tube 17 is connected with a point, the potential of which has a phase of displacement of 180° towards point 16, preferably by way of the condenser 21 with the output lead 7. In this connection system there is not only obtained an adjustment of the amplifier 3, regulable by the potentiometer 22, to an always constant medium output potential, but at the same time there is avoided an over-control into positive. The requirements 2 and 3 are accordingly fulfilled.

I claim:

1. In a television transmission arrangement comprising means for transforming the picture to be transmitted into picture contents currents, means for generating synchronisation signals having a constant amplitude exceeding the greatest amplitude of said picture contents currents, two electronic amplifiers for amplifying said picture contents currents and said synchronisation signals, said electronic amplifiers containing a plurality of electronic valves, means for coupling the stages of said electronic amplifier with one another, means for mixing the output potentials of said two amplifiers, means for generating an ultra-short carrier wave and means for modulating said mixture onto said ultra-short carrier wave, a limiting device comprising a gas-filled discharge tube having anode and cathode, a D. C. potential source, a resistance and a condenser, said anode of said discharge tube being connected by means of said condenser to the input of one of said amplifier valves of said picture current amplifier, said D. C. potential source and said resistance connected in series across the discharge space of said discharge tube, said D. C. potential source being so adjusted as to limit the output potential of said picture current amplifier as not to exceed a pre-determined value below the constant output potential of said synchronising signal amplifier.

2. In a television transmission arrangement

comprising means for transforming the picture to be transmitted into picture contents currents, means for generating synchronisation signals having a constant amplitude exceeding the greatest amplitude of said picture contents currents, two electronic amplifiers for amplifying said picture contents currents and said synchronisation signals, said electronic amplifiers containing a plurality of electronic valves, means for coupling the stages of said electronic amplifier with one another, means for mixing the output potentials of said two amplifiers, means for generating an ultra-short carrier wave and means for modulating said mixture onto said ultra-short carrier wave, a limiting device comprising a gas-filled discharge tube having anode and cathode, a D. C. potential source, resistance and a condenser, said anode of said discharge tube being connected by means of said condenser to the input of one of said amplifier valves of said picture current amplifier, said D. C. potential source and said resistance connected in series across the discharge space of said discharge tube, said D. C. potential source being so adjusted as to limit the output potential of said picture current amplifier as not to exceed a pre-determined value below the constant output potential of said synchronising signal amplifier, and a regulating device connected to the output of said picture current amplifier for regulating the amplification degree of said picture current amplifier as to give a fixed potential range for the highest and lowest amplitudes of the output potential of said picture current amplifier.

3. In a television transmission arrangement comprising means for transforming the picture to be transmitted into picture contents currents, means for generating synchronisation signals having a constant amplitude exceeding the greatest amplitude of said picture contents currents, two electronic amplifiers for amplifying said picture contents currents and said synchronisation signals, said electronic amplifiers containing a plurality of electronic valves, means for coupling the stages of said electronic amplifier with one another, means for mixing the output potentials of said two amplifiers, means for generating an ultra-short carrier wave and means for modulating said mixture onto said ultra-short carrier wave, a limiting device comprising a gas-filled discharge tube having anode and cathode, a D. C. potential source, resistance and a condenser, said anode of said discharge tube being connected by means of said condenser to the input of one of said amplifier valves of said picture current amplifier, said D. C. potential source and said resistance connected in series across the discharge space of said discharge tube, said D. C. potential source being so adjusted as to limit the output potential of said picture current amplifier as not to exceed a pre-determined value below the constant output potential of said synchronising signal amplifier, a regulating device connected to the output of said picture current amplifier for regulating the amplification degree of said picture current amplifier as to give a fixed potential range for the highest and lowest amplitudes of the output potential of said picture current amplifier, and means for adjusting the bias of said limiting device independent of an adjustment of said regulating device.
